APPARATUS FOR DETERMINING INITIAL
BOILING POINT OF LIQUIDS

William M. Mercer, Los Angeles, Calif.

Application September 17, 1945, Serial No. 616,884

19. Claims. (Cl. 73—17)

1

My invention relates to apparatus for determining the initial boiling points of liquids and has particular reference to an apparatus for accurately measuring the initial boiling point of a desired low boiling point fraction of a mixture of liquids such as a mixture of hydrocarbons.

In many industries, for example, the oil refining industry, it is the common practice to heat a mixture of a number of hydrocarbons to separate certain of the hydrocarbons from the remainder of the oil. In the production of gasoline, for example, it is the practice to treat the crude oil by heat to vaporize the lighter fractions and then to condense the gasolines to produce a gasoline hydrocarbon mixture having the desired characteristics for the type of gasoline to be produced. A desirable characteristic of such gasoline is that all undesirable highly volatile hydrocarbons should be removed, leaving only a mixture of selected hydrocarbons, the lightest desirable fraction of which determines the kind or quality of the gasoline to be produced.

Heretofore it has been the practice to attempt to maintain a uniform gasoline product by passing the gasoline mixture through a kettle where it is heated sufficiently to drive off the undesirable lighter fractions but in which an attempt is made not to heat the mixture sufficiently to drive off the lightest of the fractions desired to be kept in the finished product. In order to properly control the heat of the kettle, it has been the practice to from time to time remove a sample of the outgoing product from the kettle, the sample being conveyed to a laboratory at which the sample is brought to a temperature at which the lightest of the desired fractions starts to vaporize. That temperature is then noted and is passed back to the refinery and such alteration in the quantity of heat applied to the kettle is made in the hope that the product from the kettle will contain the lightest desired fractions and will not contain still lighter undesired fractions.

In order to maintain uniformity of product, it is apparent that the correction of the kettle temperature should be made substantially instantaneously upon the kettle heat becoming either insufficient to drive off the undesirables or becoming so great as to not only drive off the undesirables but to tend to drive off the lightest desirable fraction.

It is therefore an object of my invention to provide an apparatus in which the outgoing stream from the kettle is continuously sampled and tested for its initial boiling point (that is, the temperature at which the lightest of the desir-

2

able fractions tends to vaporize) and to permit this determination to be instantly available to the operator in control of the kettle.

Another object of my invention is to provide an apparatus of the character described in which the variation in temperature required to initially vaporize the lightest of the constituents of the hydrocarbon mixture may be employed to automatically control the heat applied to the kettle to thereby automatically maintain the quality of the resultant product uniform.

Another object of my invention is to provide an apparatus which may be connected directly to the outgoing stream from the kettle to continuously pass a sample of such stream through a testing apparatus and at which apparatus the temperature is automatically varied to cause the lightest of the desired fractions to start to vaporize and in which such temperature is so registered as to be immediately available to the operator of the kettle.

Another object of my invention is to provide an apparatus of the character described wherein the initial vaporization of the lightest of the fractions of the sample is employed to automatically heat or cool the sample to maintain a predetermined vapor pressure and in which the temperature of the sample required to maintain such fixed vapor pressure is automatically registered as the temperature at which the kettle must be maintained in order that the lightest of the fractions of the production stream should not be boiled off.

Other objects and advantages of my invention will be apparent from a study of the following specifications, read in connection with the accompanying drawings, wherein

Fig. 1 is a diagrammatic view of apparatus which may be employed to practice my invention, the various elements of which are shown in vertical section;

Fig. 2 is a detail elevational view of a temperature registering or recording chart and pen constituting a part of the apparatus shown in Fig. 1;

Fig. 3 is a detail enlarged vertical sectional view through a portion of the sample kettle shown in Fig. 1;

Fig. 4 is a detail enlarged sectional view of a safety heat cut-off which may be employed with the sample kettle shown in Fig. 1; and

Fig. 5 is a detail transverse sectional view of the safety cut-off taken along line V—V of Fig. 4.

Fundamentally the principles of my invention

comprise the continuous passing of a predetermined volume of a sample stream into a closed vessel in which the sample is subjected to either the application of heat or the application of a cooling medium sufficient to vaporize a portion of the lightest of the hydrocarbon fractions in the sample mixture, and sufficient also to maintain within the closed chamber a predetermined pressure value and in utilizing any tendency of the pressure value to increase or decrease to automatically control the application of the heat or the cooling medium to raise or lower the temperature of the sample to cause the vaporized portion thereof to remain at the predetermined selected pressure value. Thus by measuring the temperature of the sample and noting the temperature required to maintain the predetermined pressure value within the vessel, the initial boiling point of the sample mixture will be determined and this information may be utilized to control the main refinery kettle and to thus maintain the product from the kettle at a uniform value.

I accomplish this result by employing a sample vessel 1, into which is passed a continuous stream of the mixture to be measured, the quantity or volume of the sample retained within the chamber 1 being controlled by means of a valve 2 actuated by a float 3 adapted to float in the liquid of the sample within the vessel 1. The valve 2 controls the exit passage 4 from the vessel 1.

Within the vessel 1, I dispose a pressure responsive apparatus indicated generally by the reference character 5 as comprising a bellows 6 secured to the cover plate 7 of the vessel 1 in such fashion that gas pressures existing within the vessel 1 will cause the bellows 6 to expand or contract. Within the bellows 6 I dispose a pair of valves 8 and 9 (Fig. 3), the valve 8 being utilized to control the application of heat to the vessel 1 to raise the temperature of the sample therein while the valve 9 is employed to control the application of a cooling or refrigerant medium to reduce the temperature of the vessel and the sample contained therein. In this connection it should be noted that valve 8 may have a construction similar to valve 9.

Since it is desired to determine the initial boiling point of the sample, that is, the temperature at which the lightest of the hydrocarbon fractions contained within the sample will start to vaporize, I prefer to permit a sufficient quantity of the lighter fraction to vaporize to achieve within the vessel 1 some predetermined fixed pressure value, for example, five pounds per square inch. I prefer to eliminate from the mechanism employed any necessity for measuring the pressure of the sample and to depend for the creation of pressure within the vessel 1 solely upon the quantity of the sample vaporized within the vessel 1.

To accomplish this purpose, I lead the sample stream from a pipe 10 connected to the output end of the refinery kettle through a filter 11 and thence through a pressure reducing valve 12 to insure that the incoming stream of sample will be passed into the vessel 1 at some fixed predetermined pressure value. Since it is desirable to maintain a predetermined volume of the sample within the vessel 1, I pass the sample stream through an orifice member 13, the opening through which is smaller than the exit opening through the float controlled valve 2. Thus the volume of the sample within the vessel 1 and

the pressure of the incoming sample are both maintained at constant values.

In order to vaporize a portion of the lighter fractions of the sample stream within the vessel 1, it may be necessary to apply heat to the vessel 1 and this may be readily accomplished by any suitable means such as a heating coil 14 adapted to be supplied with electric current through a control switch 15. The coil 14 is disposed about the lower portion of the vessel 1 immediately adjacent the float 3. On the other hand, it may be that the incoming sample stream is at a temperature sufficiently high to vaporize a portion of the lighter fractions of the sample, in which event it may be necessary to apply a cooling or refrigerant medium to the vessel 1 to lower the temperature of the sample under test. This would be particularly true of liquids to be tested which have desirable fractions which would boil at atmospheric temperatures requiring cooling, which may be readily accomplished by providing a cooling chamber 16 between the vessel 1 and an outer jacket 17, through which chamber a cooling refrigerant medium from a suitable source, indicated at 18, may be circulated under the control of a refrigerant valve 19 and an orifice 20. The cooling medium is permitted to enter the chamber 16 through a suitable entry port 21 and to be exhausted through an exhaust or return pipe 22.

To effectively control the switch 15 for the heating element 14, I mount the switch 15 to be actuated under the influence of air pressure from a suitable source of air pressure indicated by the pipe 23. The air pressure from such source is passed through a filter 24, a pressure regulator valve 25 and a flow limiting orifice 26 to a distribution pipe 27, one branch of which is connected to a Bourdon tube 28 operatively connected to the switch 15 to hold switch 15 in circuit closing position whenever pressure from the source 23 is applied thereto and permitting the switch 15 to move to its open position when the pressure in the Bourdon tube 28 is released.

The control of the switch 15 is accomplished by the valve 8 which, as will be noted from an inspection of Fig. 3, comprises a valve tube 29 having upon its upper end a head 30 slidably mounted upon guides 31 in a valve housing 32, the tube 29 being normally urged upwardly in the housing 32 by means of a spring 33 but limited in its upward movement by means of an adjusting screw 34 threaded into a plug 35 in the upper end of the housing 32 in such manner that the lower end of the screw 34 will bear upon the head 30 and hold the valve tube 29 at some fixed predetermined level with respect to an operating plate 36 disposed upon the bottom of the bellows 6.

By adjusting the position of the tube 29 relative to the plate 36, the valve stem 37 in the lower end of the tube 29 will be caused to be lifted when the bellows 6 is subjected to a predetermined value of vapor pressure within the vessel 1, the pressure required to operate the valve stem 37 being adjusted by raising and lowering the adjusting screw 34 to select the desired operating value.

The valve stem 37 is arranged to operate a poppet valve, such as that illustrated at 38, the poppet valve being normally closed to prevent the escape of air pressure from the source 23 extending through the branch pipe 39 to the interior of the valve tube 29 but adapted, when actuated 75 by engagement with the plate 36, to exhaust the

air from the branch pipe 39 through a vent 48 in the valve housing 32 and thus permit the reduction in pressure of the air effective upon the Bourdon tube 28. By making the valve 37 of larger flow capacity than the orifice 26, it will be apparent that the opening of the valve 37 will result in the substantial exhaustion of air pressure from the Bourdon tube 28 and the consequent opening of the switch 15.

Thus it will be observed that the necessary heat will be applied to the sample within the vessel 1 to vaporize a portion of the lighter fractions of the sample mixture until the predetermined fixed vapor pressure has been attained and thereafter the application of heat will be stopped until the vapor pressure within the vessel 1 tends to reduce below the selected pressure, at which time the valve 37 will again close and the air pressure from the source 23 will be effective to reclose the switch 15 to supply additional heat to the sample within the vessel 1. By properly selecting the pressure value for the setting of the valve 8-37, only a portion of the lightest of the desired fractions in the sample will be vaporized and the quantity of heat necessary to cause this partial vaporization will be supplied to the vessel 1. Thus by measuring the temperature within the vessel 1, the temperature at which the lightest of the fractions will start to vaporize is determined and this value is the initial boiling point for the sample under measurement.

While the cutting off of a supply of heat to the vessel 1 will result in the lowering of the temperature of the vessel, it is desirable to accelerate the reduction in temperature by the application of the cooling or refrigerant medium, particularly in instances in which the incoming sample stream is at a relatively high temperature as it enters the vessel and the regulation of the application of the cooling or refrigerant medium to the vessel 1 may be readily controlled by means of the valve 9 within the bellows 6 by setting the position of the valve tube 40 to a position relative to the plate 36 as to cause the valve 38 in the valve tube 9 to be opened by a minute increase of vapor pressure within the vessel 1 over the pressure at which the valve 37 operates. The differential between the pressure values required to operate the valve 37 and to operate the valve 38 may be extremely small, for example, .02 pound per square inch, so that any tendency of the pressure within the vessel 1 to rise above the value selected by the setting of the valve 8-37 will immediately result in the application of the cooling or refrigerant medium to the vessel.

The operation of the valve 38 in valve tube 9 is employed to control the refrigerant valve 19 (Fig. 1) as by extending a branch 41 of the air pressure supply pipe through a pilot valve 42 and thence by way of a pipe 43 to a control chamber 44 associated with the valve 19 in such manner that the air pressure is exerted upon a bellows 45 to cause a movable valve member 46 to normally close upon a valve seat 47 and prevent the passage of refrigerant medium to the vessel 1.

The pilot valve 42 is a normally open valve adapted to be closed by the application of air pressure to an actuating bellows 48 which will move a movable valve member 49 from the normal position illustrated in Fig. 1 to another position in which the movable valve member seats upon a seat 50 while at the same time the movable valve member is moved away from an auxiliary seat 51, permitting the exhaustion of air pressure through the pipe 43 and valve seat 51.

and through a vent 52 to the atmosphere. While the valve 42 may be used to control the main refrigerant valve 19 directly, a more rapid and sensitive operation of the valve 19 will be accomplished by interposing an auxiliary control valve 53 immediately ahead of and adapted to control the pilot valve 42. The auxiliary valve 53 is subjected to pressure from the air pressure source through an orifice member 54 connected in a pipe line, one branch 55 of which extends to a bellows chamber in the valve 53 to normally hold the movable valve member 56 thereof in closed position, as shown in Fig. 1, while the other branch 57 of the pipe line extends to the valve 9 through the bellows 6.

It will be apparent that as long as the valve member 38 in the valve 9 remains in its closed position, the effect of pressure from the air pressure source will be imposed upon the auxiliary valve 53 to maintain the movable valve member 56 thereof in the position shown in Fig. 1, permitting the exhaustion of air pressure from the bellows 48 in pilot valve 42 through the normally open valve portion 58 and through a vent 59 to the atmosphere while immediately upon opening the valve member 38 by an increase in vapor pressure within the vessel 1 above the selected pressure value, the air pressure from the source 23 will be exhausted from the bellows within the auxiliary valve 53, allowing the movable valve member 56 thereof to move to open position and to supply the necessary air pressure to the bellows 48 of the pilot valve 42 to close the valve member 49 and to thereby permit exhaustion of air from the main control valve 19.

Thus the operation of the main valve 19 will supply cooling medium to the vessel 1 to cause a rapid reduction in the temperature thereof until the temperature within the vessel 1 is just sufficient to maintain vaporized a portion of the lightest of the fractions of the sample stream.

From the foregoing it will be apparent that a continuous sample stream passing through the vessel 1 is automatically regulated as to temperature to cause the vaporization of only the lightest of the lighter fractions and that fluctuations in the temperature necessary to maintain this portion of the lighter fractions vaporized will be automatically recorded by a temperature recorder 60 which may be of any suitable construction. As illustrated in Figs. 1 and 2, the temperature recorder comprises a temperature responsive instrument 61 which may be a helix of thermometal coupled to a shaft 62 in such fashion as to rotate the shaft 62 in response to variations in temperature within the vessel 1, the shaft 62 having secured thereto an arm 63 adapted to sweep across a record chart or disk 64 to draw a curve corresponding to temperature variations within the vessel 1.

By noting the position of the pen on the chart, an operator may readily adjust the temperature applied to the refinery kettle to raise or lower the temperature of the kettle so as to effectively drive off the lighter undesirable fractions and to insure the retention of the lightest desirable fractions in the product from the kettle.

Since most volatile liquids contain minute amounts of components which cannot be readily condensed, or re-absorbed, in the ordinary processes of distillation, I prefer to provide a vent 65 connected to the upper portion of vessel 1 and having connected thereto an orifice member 66 having an extremely small orifice therein which

will permit such minute amounts of uncondensables to escape. This prevents the control mechanism of the instrument from operations due to the collection of such gases, which tend to create a false pressure condition within the vessel 1. The vent 65 also acts to continuously remove the vapor of the lightest fraction.

If desired, a pressure gauge 70 may be connected in the sample line between the pressure regulating valve 12 and the vessel 1 to give a continuous indication of the pressure in the sample stream while pressure gauges 71 and 72 interposed in the air pressure lines 57 and 58 may be employed to effectively register the operativeness of the valves 9 and 8, respectively. Similarly, if desired, pressure gauges 73 and 74 may be interposed in the air pressure line immediately in advance of the pilot valve 42 and the cooling medium control valve 19 to effectively register the operativeness of these valves.

While the switch 15 may be of any suitable construction, it is desirable to employ a non-arcing switch such as a mercury switch such as illustrated in Fig. 1, and it is further desirable to enclose the same in a suitable vapor-proof housing such as is illustrated at 75 when the instrument is to be employed in connection with highly volatile and inflammable materials such as gasolines and the like.

It may also be desirable to add a safety feature to the vessel 1 to prevent the inadvertent overheating thereof. One form of such safety device is illustrated in Figs. 1 and 4 as comprising a temperature measuring instrument 76 of the helical thermo-metal type, the shaft 77 of which has a flanged head 78 secured thereto and disposed below the bottom of the vessel 1. The shaft 77 is preferably guided through a bearing member 79 threaded into the lower end of the vessel 1 and has a groove 80 formed upon its periphery for the reception of a plurality of screws 81 or other supports for a housing 82. The housing 82 has at its lower end a valve 83 normally closed by means of a spring 84 but adapted to be opened by a weight 85 when the weight is released by the flanged head 78. The weight 85 is illustrated as being in the form of a cup, upon opposite side walls of which are mounted pins 86, one end of each of the pins being slidably guided in longitudinal slots 87 formed upon the interior of the housing 82 while the opposite ends of each of the pins overlie the flanged head 78 at all times except when the flanged head 78 is rotated under the influence of the temperature measuring element 76 to a position to align a pair of slots 88 with the pins 86.

By rotating the housing 82 relative to the bearing member 79, the position of the pins 86 relative to the slots 88 may be adjusted so that the predetermined temperature which must be attained by the temperature measuring device 76 before sufficient rotation of the head 78 will occur to align the slots 88 with the pins 86 may be readily adjusted.

It will be apparent therefore that by setting the housing 82 at some desired position relative to index marks 89 on the bearing member 79, the maximum heat which can be attained by the vessel 1 will be predetermined, the attainment of such predetermined heat resulting in the rotation of the shaft 77 and the head 78 to align the slots 88 and the pins 86 in such position that the cup weight 85 which has been previously supported by the flanged head 78 will be released and will be urged by spring 85a upon the valve 83, open-

ing this valve against the force of its biasing spring 84.

It will be noted that the housing 82 is provided with a pair of openings 90 and 91, the opening 90 being connected by means of a suitable piping 92 to the same branch pipe 27 as is employed to supply air under pressure to the Bourdon tube 28 controlling the switch 15, while the opening 91 constitutes a vent to the atmosphere so that upon the opening of the valve 83 the Bourdon tube 28 will be vented to atmospheric pressure and the switch 15 will be moved to its open circuit position, as was described with reference to the operation of the main control valve 8.

From the foregoing it will be apparent that I have provided an apparatus in which a sample stream of any mixture of liquids may be tested continuously to determine the initial boiling point of the liquid or liquid mixture under test and by which the initial boiling point is detected by reason of the start of the vaporization of the lightest of the fractions in the liquid under test. It will also be apparent that by utilizing a predetermined pressure responsive mechanism in connection with the testing of the sample stream, the initial boiling point will be denoted by the temperature which is required to start the vaporization of the lightest fraction of the liquid. Hence by noting the required temperature to start such vaporization, not only is the information obtained as to what is the initial boiling point but the temperature information is available to be employed for the purpose of controlling the refinery kettle to insure the production from the refinery being maintained at a constant value of initial boiling point.

While I have shown and described the preferred embodiment of my invention, I do not desire to be limited to any of the details of construction shown and described herein, except as defined in the appended claims.

I claim:

1. In an apparatus for determining the initial boiling point of liquids, a vessel, flow control means for maintaining a continuous stream of the liquid to be tested passing through said vessel and including an automatic valve for maintaining within said vessel a predetermined volume of the liquid under test, thermal transfer means for maintaining the vapor pressure within said vessel at a predetermined fixed value, and means for measuring the temperature of the vessel required to maintain said predetermined vapor pressure.

2. In an apparatus for determining the initial boiling point of liquids, a vessel, means for maintaining a continuous stream of the liquid to be tested passing through said vessel, means in said vessel for maintaining within said vessel a predetermined volume of the liquid under test, a vapor flow control device for maintaining the vapor pressure within said vessel at a predetermined fixed value, means for measuring the temperature of the vapor maintained at said predetermined vapor pressure, means for applying a heating medium to said vessel to cause the liquid therein to vaporize sufficient to attain said predetermined vapor pressure, and an actuator responsive to the vapor pressure within said vessel for controlling the quantity of the heating medium applied to said vessel.

3. In an apparatus for determining the initial boiling point of liquids, a vessel, means for maintaining a continuous stream of the liquid to be

tested passing through said vessel, means in said vessel for maintaining within said vessel a predetermined volume of the liquid under test, a vapor control mechanism for maintaining the vapor pressure within said vessel at a predetermined fixed value, means for measuring the temperature of the vessel required to maintain said predetermined vapor pressure, thermal transfer means for applying a heating medium or a cooling medium to said vessel to cause the liquid therein to vaporize sufficiently to attain said predetermined vapor pressure and including a source of heat and a heat absorber, and means responsive to changes in the vapor pressure within said vessel for controlling the quantity of the heating medium and cooling medium applied to said vessel.

4. In an apparatus for determining the initial boiling point of liquids, a vessel, means for maintaining a continuous stream of the liquid to be tested passing through said vessel, valve means in said vessel responsive to vapor pressure existing within said vessel, means for supplying a heating medium and a cooling medium to said vessel to cause the liquid therein to become partially vaporized, means actuated in response to operation of said valve means when the vapor pressure within said vessel reaches a predetermined fixed value for controlling the application of the heating medium to said vessel, means actuated by said valve means when the pressure within said vessel reaches a predetermined value in excess of said first named value for controlling the application of the cooling medium to said vessel, and means associated with said vessel for registering the temperature of said vessel required to attain said predetermined vapor pressure values.

5. In an apparatus for determining the initial boiling point of a liquid, a vessel, means for passing a continuous stream of the liquid to be tested passing through said vessel, means for regulating the pressure of the liquid entering said vessel at a predetermined fixed pressure value, means for maintaining the rate of flow of the incoming stream of liquid at a fixed value, float actuated valve means in said vessel having a capacity in excess of the fixed flow value of the incoming stream for maintaining a predetermined volume of said liquid in said vessel, means associated with said vessel for regulating the temperature in said vessel for vaporizing a portion of the liquid in the sample under test, means responsive to the attainment of a predetermined vapor pressure within said vessel for controlling the temperature regulating means to maintain the vapor pressure within said vessel at a predetermined fixed value, and means for registering the temperature of said vessel required to maintain said predetermined vapor pressure.

6. In an apparatus for determining the initial boiling point of a liquid, a vessel, means for passing a continuous stream of liquid under test into said vessel, flow control means associated with said vessel for maintaining within said vessel a predetermined volume of said stream of liquid under test, means for applying heat to said vessel, control means for controlling the quantity of heat supplied to said vessel, valve means in said vessel responsive to the attainment of a predetermined pressure within said vessel, a source of fluid under pressure, means for supplying fluid from said source to said heat control means to actuate said control means to apply heat to said vessel, and means responsive to actuation of

7. In an apparatus for determining the initial boiling point of a liquid, a vessel, means for passing a continuous stream of liquid under test through said vessel, means associated with said vessel for maintaining within said vessel a predetermined volume of a stream of liquid under test, means for applying heat to said vessel, control means for controlling the quantity of heat supplied to said vessel, valve means in said vessel responsive to the attainment of a predetermined pressure within said vessel, a source of fluid under pressure, means for supplying fluid from said source to said temperature control means to actuate said control means to apply heat to said vessel, means responsive to actuation of said valve means for exhausting said pressure fluid from said temperature control means to cut off the application of heat to said vessel.

5 8. In an apparatus for determining the initial boiling point of a liquid, a vessel, means for passing a continuous stream of liquid under test through said vessel, means associated with said vessel for maintaining within said vessel a predetermined volume of a stream of liquid under test, means for applying heat to said vessel, control means for controlling the quantity of heat supplied to said vessel, valve means in said vessel responsive to the attainment of a predetermined pressure within said vessel, a source of fluid under pressure, means for supplying fluid from said source to said temperature control means to actuate said control means to apply heat to said vessel, means responsive to actuation of said valve means for exhausting said pressure fluid from said temperature control means to cut off the application of heat to said vessel, means for supplying a cooling medium to said vessel, a second valve means responsive to the attainment of a vapor pressure within said vessel in excess of that required to operate said first valve means, a control means for controlling the supply of said cooling medium to said vessel, means for applying the pressure fluid to said control means for actuating said control means to cut off the supply of cooling medium to said vessel, and means responsive to actuation of said second valve means for exhausting said pressure fluid from said cooling medium control means to cause said control means to apply cooling medium to said vessel during such periods as the vapor pressure within said vessel exceeds said first named predetermined value.

40 9. In an apparatus for determining the initial boiling point of a liquid, a vessel, means for passing a continuous stream of liquid under test through said vessel, means associated with said vessel for maintaining within said vessel a predetermined volume of a stream of liquid under test, means for applying heat to said vessel, control means for controlling the quantity of heat supplied to said vessel, valve means in said vessel responsive to the attainment of a predetermined pressure within said vessel, a source of fluid under pressure, means for supplying fluid from said source to said heat control means to actuate said control means to apply heat to said vessel, means responsive to actuation of said valve means for venting said pressure fluid from said heat control means to cut off the application of heat to said vessel, and a safety device responsive to the attainment of a predetermined temperature in said vessel for actuating said temperature control means to cut off further supply of heat to said vessel.

45 10. In an apparatus for continuously determining the initial boiling point of a liquid mixture, a vessel adapted to receive a sample of the mixture, a metered liquid inlet for the vessel, a metered vapor outlet for the vessel, a float valve to maintain a pool of liquid within the vessel and to regularly eject a portion of the liquid, a thermal transfer mechanism for the vessel, a pressure responsive control for the thermal transfer mechanism whereby excessive pressure causes subtraction of heat and deficient pressure causes addition of heat, and a temperature indicator for the vapor within the vessel.

50 11. In an apparatus for continuously determining the initial boiling point of a liquid mixture, a vessel adapted to receive a sample of the

mixture, a metered inlet for the liquid sample, a metered outlet for vapor from the sample, a float valve to maintain a pool of liquid in the vessel, a heater for the vessel, a cooler for the vessel, a pressure operated control for actuating the heater, a control for the cooler operable upon release of pressure, a member movable in response to the vapor pressure within the vessel, and a valve associated with the heater control and the cooler control and adapted to be operated by the movable member, whereby excessive pressure within the vessel will actuate the heater control valve to release pressure in the heater control and thereby de-energize the heater, and whereby excessive pressure within the vessel will actuate the cooler control valve for energizing the cooler, thereby effecting automatic subtraction or addition of heat in response to the pressure within the vessel.
